UNITED STATES PATENT OFFICE.

LOUIS C. HILLER, OF MERIDEN, CONNECTICUT, ASSIGNOR TO THE MERIDEN SILVER PLATE COMPANY, OF SAME PLACE.

DESIGN FOR A CLOCK-CASE.

SPECIFICATION forming part of Design No. 16,591, dated March 30, 1886.

Application filed February 1, 1886. Serial No. 190,390. Term of patent 7 years.

To all whom it may concern:

Be it known that I, LOUIS C. HILLER, a citizen of the United States, residing at Meriden, in the county of New Haven and State of Connecticut, have invented and produced a new and original Design for Clock-Cases, of which the following is a specification, reference being had therein to the accompanying drawing, which is an elevation of a clock-case embodying my novel design.

My design consists in the representation of a bundle of cigars crossed by two horizontal bands, one near the top and the other near the bottom of the said bundle, a raised circular panel between the said bands, and a dial within the said panel.

1 denotes the representations of the pointed ends of the cigars at the top of the case, and 2 the representations of the tips of the cigars at the bottom thereof.

3 denotes representations of the strips of leaf forming the wrappers, and 4 representa-

tions of two horizontal bands, one near the top and the other near the bottom of the bundle.

Between the upper pointed ends of the cigars 25 are notches 5, and between the horizontal bands 4 is a raised circular panel, 6, inclosing a clock-dial, 7.

Having thus described my invention, I claim—

The design for a clock-case herein shown, the same consisting of the representation of a bundle of cigars, the representations of two horizontal bands, one near the top and the other near the bottom of the said bundle, a circular panel between said bands, and a dial within said circular panel, as set forth.

In testimony whereof I affix my signature in presence of two witnesses.

LOUIS C. HILLER.
